UNITED STATES PATENT OFFICE.

MARY M. EVERHARD, OF ST. JOSEPH, MICHIGAN.

KNEADING-BOARD.

SPECIFICATION forming part of Letters Patent No. 445,443, dated January 27, 1891.

Application filed November 13, 1890. Serial No. 371,193. (No model.)

To all whom it may concern.

Be it known that I, MARY M. EVERHARD, a citizen of the United States, residing at St. Joseph, in the county of Berrien and State of Michigan, have invented certain new and useful Improvements in Kneading-Boards; and I do declare the following to be a full, clear, and exact description of the invention, such as will enable others skilled in the art to which it appertains to make and use the same.

This invention has relation to a molding or kneading board for culinary purposes. An important desideratum in this class of devices has been to produce a board which will not take stain or grease, will always have a smooth surface, a cool temperature, will be light and durable, and will not sour, and may be easily cleansed. To produce such an article at a minimum expense is the object of my invention; and with such end in view I shall proceed to describe in detail the construction of such invention.

Reference may be had to the accompanying drawings and to the letters of reference thereon, in which—

Figure 1 is a perspective view of my improved board or tray, and Fig. 2 is a cross-sectional view of the same.

In carrying out my invention I take a sheet of metal or other suitable material of sufficient length and width and bend or shape the same so as to form one end into a transverse wall *a*, which is carried upwardly at approximately right angles to the body portion *A*, and in the upper edge of this wall *a* may be inserted a wire *b*, to give strength and durability to said article. I also bend or shape the opposite side edges so as to form shallow vertically-disposed walls *c c*, which taper from their inner to their outer ends, as shown, and

I also turn up slightly the outer transverse edge, as shown at *d*.

From the construction illustrated it will be seen that the top surface of the board is perfectly smooth and flat, although depressed with respect to its marginal edges, and that the lateral vertically-disposed edges slope from their upper or inner ends to their outer ends. This formation, while presenting the advantages of keeping the dough or flour from wasting off of the board, may in some instances render the board very convenient in dipping up the flour as a scoop, if made of a suitable size for that purpose. These articles may be formed from granite-ware or from any sheet metal, and in some cases the surface may be finished by any polishing process.

B indicates a ring, which will be found convenient for suspending the board from a hook, nail, or the like, when not in use.

Having described my invention, what I claim is—

1. As an improved article of manufacture, a molding or kneading board formed from sheet metal and having the rear vertically-disposed integral wall *a*, and the lateral walls tapering from their inner to their outer ends and the shallow outer transverse edge, substantially as specified.

2. A molding or kneading board formed from sheet metal, and having its marginal edges turned slightly upward from the body portion, the rear edge being of a greater elevation than the forward edge, substantially as specified.

In testimony whereof I affix my signature in presence of two witnesses.

MARY M. EVERHARD.
